ABSTRACT: A weekly switching device, for a time switch including a rotating dial and a switch-operating tappet adjustably mounted thereon for rotation therewith at an angular position representing the time of day, includes a stepping wheel mounted rotatably on the tappet and having a number of stepped positions evenly divisible by seven and representing days of the week. The stepping wheel is advanced one step during each revolution of the daily dial. Switch controlling means are selectively associated with the stepped positions and operate to make ineffective operation of an electric switch by the tappet, at the time of day represented by the angular position of the tappet, on the day represented by the selected stepped position of the switch controlling means.

WEEKLY SWITCHING DEVICE FOR TIME SWITCH
HAVING A ROTATING DAILY DIAL

BACKGROUND OF THE INVENTION

Known switch tappets, for time switches having rotating daily dials, are arranged close to the periphery of the daily dial for operative association with the operating means of an electric switch, such as a time or locking switch. The switch tappets preferably are arranged on a diameter of the daily dial. In such arrangements, the operating means of a time switch, and which extend into the path of the switch tappets, also may be positioned in a plane parallel to the daily dial and other than that of the corresponding switch tappets operatively engageable with the operating means.

All known time switch arrangements of this type, however, provide for only so-called daily switching, while so-called weekly switching, such as a switching operation performed only from 1 to 6 times per week, can be effected only by means of an additional weekly dial. Switching devices actuated by known weekly dials have the disadvantage that there are tolerances in time so that, in many instances, a weekly program can be carried out only with complicated and thus expensive means.

For reasons of space, time switches used for higher switching efficiency usually comprise only one switch. Such switches are provided, inter alia with devices for a "switched-on" or "switched-off" locking for predetermined days, with the weekly dial actuating the locking devices on predetermined days of the week through the medium of tappets, segments, or other switching or control means. Arrangements of this type have, however, the disadvantage of requiring several different constructions of the switch, so that the switch, together with the weekly dial, constitutes an expensive but not versatile arrangement.

Another known embodiment of a weekly dial for a time switch provides an elevational displacement of the time disc or of the operating means of the electric switch, thus providing for omission of certain switching operations at predetermined times or on predetermined days. In arrangements of this type, the week customarily is divided into 14 parts, with each day being divided into two optional periods. While these 14 parts into which the week is divided may be set selectively to be operative or inoperative, the switching affects all tappets related to a particular part of the week. The operation of such a weekly dial is very complicated and, moreover, this weekly dial does not constitute a versatile or economical solution to the problem of weekly switching.

SUMMARY OF THE INVENTION

This invention relates to time switches including rotating daily dials and, more particularly, to an improved weekly switching arrangement for such time switches, and which provides very much more exact and versatile weekly switching than possible with known weekly dials.

In accordance with the invention, the weekly switching arrangement comprises a continuous switching wheel, in the form of a stepping wheel, rotatably mounted on the daily dial such as, for example, being rotatably mounted on the switch tapped adjustably mounted on the daily dial. This stepping or switching wheel is advanced one step during each revolution of the daily dial, and has a number of switching positions which is evenly divisible by seven. That is, the number of switching positions may be seven or may be a multiple of seven. Switch controlling means may be selectively associated with each step position of the stepping wheel, and switching means cooperate with the stepping wheel in a manner such that, when an associated switching tappet operatively engages the operating means of an electric switch operated by the "daily" switch tappet, the weekly switching is effected at the time of day representing the angular position of the "daily" switch tappet on the rotating daily dial.

An object of the invention is to provide an improved weekly switching arrangement for time switches including a rotating daily dial.

Another object of the invention is to provide such a weekly switching arrangement which is considerably more exact and versatile than hitherto known weekly dials.

A further object of the invention is to provide such a weekly switching arrangement which operates at the time of day represented by the angular position of the "daily" switch tappet on the daily dial.

Another object of the invention is to provide such a weekly switching arrangement including a rotatable stepping wheel having a number of stepping positions evenly divisible by seven and which is advanced by one step during each revolution of the daily dial.

For an understanding of the principles of the invention, reference is made to the following description of a typical embodiment thereof as illustrated in the accompanying drawings.

BRIEF DESCRIPTION OF THE DRAWINGS

In the Drawings:

FIG. 1 is a side elevation view of a known switch tappet for time switches having a rotating daily dial, the daily dial being shown only partly and in section;

FIG. 2 is a top plan view of the weekly switching device of the present invention;

FIG. 3 is a side elevation view, partly in section, of the weekly switching device shown in FIG. 2;

FIG. 4 is a bottom plan view of the weekly switching device shown in FIG. 2;

FIG. 5 is a view, similar to FIG. 1, illustrating a "weekly" tappet;

FIG. 6 is a view, similar to FIG. 5, illustrating the "weekly" tappet in the disengaged position;

FIG. 7 is a top plan view of a simple double throw switch, showing the paths of two operating pins;

FIG. 8 is a view, similar to FIG. 1, illustrating a switch operating on a different principle and requiring only one pin path; and

FIG. 9 is a side elevation view illustrating a friction coupling providing for adjustment of a switching lever relative to a daily dial.

DESCRIPTION OF THE PREFERRED EMBODIMENTS

Referring to FIG. 1, which illustrates a known form of daily switching arrangement for a time switch including a rotating daily dial, a known switch tappet 1 is secured to the periphery of a daily dial 3, which has not been shown in detail, by means of a screw 2. In a known manner, switch tappet 1 comprises two selectively insertable switch pins 4 and 5 for "on" and "off" operations, respectively. These switch pins cooperate with the operating means of an electric switch forming part of the time switch, and actuate the operating means at the time of day represented by the angular position of switch tappet 1 on daily dial 3. Thus, operations may be effected once during each revolution of the daily dial, i.e., every 24 hours.

Referring to FIGS. 2, 3 and 4, in the invention arrangement, a switch tappet 1' is secured to daily dial 3 in the same manner as the switch tappet 1 of FIG. 1. Switch tappet 1' is mounted on daily dial 3 at or adjacent the periphery thereof by means of the screw 2 which engages into a slot or groove 6 in daily dial 3. Tappet 1' rotatably supports a star wheel or stepping wheel 7 which, in the illustrated embodiment, comprises seven projecting fingers or studs 8 which are numbered in correspondence with the days of the week.

A driving pin 9 is attached to the stationary indicator (not shown) of a time switch and, once during each revolution of daily dial 3 in the direction of the arrow shown in FIG. 2, advances stepping wheel 7 by one step, i.e., by one day of the week. Stepping wheel 7 is releasably latched in each step position by a leaf spring 10 secured, for example, in fixed position 75 on tappet 1'.

Wheel 7 is rotatably supported on an axle or pivot 11 fixedly connected to a plate 12 lying in a plane parallel to that of daily dial 3. In turn, plate 12 is secured against angular movement by means of a guide pin 13 secured in tappet 1' and extending through an aperture in plate 12. On the underside of stepping wheel 7 there is provided a radial takeup cam 14 explained in detail hereinafter.

Axle or pivot 11 of star wheel 7 is subjected to the bias of a small coil spring 15, positioned between tappet 1' and an abutment on the upper end of pivot or shaft 11, and biasing plate 12 upwardly. It will be noted that plate 12 is movable longitudinally of guide pin 13, toward and away from stepping wheel 7.

In the illustrated embodiment, plate 12 is formed with seven threaded holes or apertures 16, as best seen in FIG. 4, which are arranged on a circle concentric with the axis of shaft 11 and at equal angular spacings. These apertures 16 are numbered "1" to "7", in correspondence with the studs or fingers 8. Pins 17 may be screwed into selected threaded holes 16, thereby to actuate the weekly switching, by the respective pins 17, at the time of day represented by the angular position of tappet 1' on daily dial 3. This actuation is effected by functional cooperation of a selectively positioned pin 17 with the cam 14 on the underside of stepping wheel 7. As in the known switch tappet 1 of FIG. 1, the "weekly switching tappet" 1' of FIGS. 2, 3 and 4 also mounts a "switch-on" pin 4 or a "switch-off" pin 5, or both.

When, for example, a pin 17 inserted into the threaded hole 16 at the "1" position, engages takeup cam 14 and, when stepping wheel 7 is advanced into the next stepping position, plate 12 is pressed downwardly, against the bias of spring 15, so that a switching pin 4 or 5 controls the operating elements of the electric switch of the time switch, to effect operation of the electric switch by a "daily" tappet 4 or 5. The pins 17 thus constitute switching controlling means.

When pin 17 moves out engagement with cam 14 of stepping wheel 7, plate 12 is biased back to its rest position by spring 15. After a complete revolution of daily dial 3, stepping wheel 7 is advanced one step by the stationary driving pin 9, despite the releasable latching operation of leaf spring 10. If, in this next stepping position of wheel 7, there is no pin 17 in the corresponding threaded hole 16 at position "2" of plate 12, plate 12 is not moved downwardly and, accordingly, the electric switch is not controlled by a switching pin 4 or 5.

In a modification of the invention arrangement, the switching tappet of the invention need not be positioned on daily dial 3, but may be positioned on a switching lever extending radially of daily dial 3 and being adjusted, in a known manner, to the desired time of day of the daily dial, by means of a friction coupling.

FIGS. 5, 6 and 7 illustrate the cooperation of the pin or tappet 4 with a simple switch comprising an operating member 25, engageable with tappet or pin 4, and oscillatable with a movable switch contact arm 26 which is cooperable with either of a pair of fixed contacts 27 or 28. FIG. 5 illustrates the arrangement with tappet 4 in a position to engage operating arm 25, and FIG. 6 illustrates the arrangement of the parts when tappet 4 is moved to a position where it cannot engage the arm 25.

FIG. 8 illustrates a further form of simplified switch which is operable by the tappet 4, and which comprises a normally closed switch 30 which is operable by a star-shape operating member 31, engaged by tappet or pin 4, which in turn operates a cam 32 engageable with a longer arm of switch 30.

FIG. 9 illustrates the invention arrangement including a daily dial, switching levers, and a switching coupling. Referring to FIG. 9, a switching lever 18 is frictionally coupled to the daily dial 3 through the medium of a washer 19, a spring washer 20, a nut 21, and a nut 22. There are two levers 18

which, with washer 19 interposed therebetween, are pressed together, and with relation to daily dial 3, by spring washer 20 to form a friction coupling allowing the levers to be set to the desired time. The left side of FIG. 9 illustrates weekly tappet 1 fixed on one lever 18, and illustrates pins 4 or 5 on the other lever 18.

I claim:

1. In a time switch including a rotating daily dial and a switch tappet adjustably mounted on the daily dial, for rotation therewith, at an angular position representing the time of day at which a switching operation is to be effected by engagement of the tappet with operating means of an electric switch: the improvement comprising, in combination, a stepping wheel mounted rotatably on said tappet and having a number of step positions which is evenly divisible by 7, and which represent days of the week; means operable, in conjunction with rotation of said daily dial, to advance said stepping wheel one step during each revolution of said daily dial; and switch controlling means selectively associated with said step positions and making ineffective operation of said electric switch by said tappet, at the time of day represented by the angular position of said tappet, on the day represented by the selected step position of said switch controlling means.
2. In a time switch including a rotating daily dial, the improvement claimed in claim 1, in which said switch controlling means includes cam means and individual switch controlling elements selectively associated with said step positions in any desired pattern, said individual switch controlling elements being cooperable with said cam means.
3. In a time switch including a rotating daily dial, the improvement claimed in claim 2, including a plate operatively associated with said stepping wheel; said individual switch controlling elements comprising studs mountable on said plate; pin means on said plate operably engageable with said electric switch in an operative position of said plate; and means biasing said plate to an inoperative position; said cam means being rotatable with said stepping wheel and cooperable with said studs to move said plate to its operative position for each step position in which a stud is present.
4. In a time switch including a rotatable daily dial, the improvement claimed in claim 1, in which said stepping wheel is a star wheel; said stepping wheel advancing means comprising a fixedly positioned driving pin on said time switch engageable with said star wheel to advance the same once during each rotation of said daily dial.
5. In a time switch including a rotating daily dial, the improvement claimed in claim 4, including releasable latch means releasably retaining said star wheel in each stepped position.
6. In a time switch including a rotating daily dial, the improvement claimed in claim 4, including a cam on one surface of said star wheel; a plate adjacent said one surface of said star wheel and carrying pin means, said plate having an operative position in which said pin means are operatively associated with said electric switch, and having an inoperative position in which said pin means are out of operative association with said electric switch; said plate formed with a plurality of apertures arranged on a circle concentric with the axis of rotation of said star wheel, and the number and position of said apertures corresponding to the number and position of said step positions; means biasing said plate to the inoperative position; and at least one stud selectively engageable in a selected one of said apertures for cooperation with said cam means to move said plate to the operative position.
7. In a time switch including a rotating daily dial, the improvement claimed in claim 1, including a switching lever removably mounting said tappet; and a friction coupling providing for adjustment of said switching lever relative to said daily dial.
